UNITED STATES PATENT OFFICE.

LE ROY BALL AND AUGUSTUS L. MCLEAN, OF ASHEVILLE, NORTH CAROLINA.

FLUSHING APPARATUS.

1,237,276.

Specification of Letters Patent. Patented Aug. 21, 1917.

Application filed January 13, 1917. Serial No. 142,280.

To all whom it may concern:

Be it known that we, LE ROY BALL and AUGUSTUS L. MCLEAN, citizens of the United States, residing at Asheville, in the county of Buncombe and State of North Carolina, have invented certain new and useful Improvements in Flushing Apparatus; and we do hereby declare the following to be a full, clear, and exact description of the invention, such as will enable others skilled in the art to which it appertains to make and use the same:

This invention relates to flushing apparatus, and particularly to flush tanks. It is an object of the present invention to provide a flush tank in which the water tank for refilling the tank may enter through a valve which is normally open until the main tank is substantially filled with water and is then quickly closed by an automatic valve.

It is a further object of the present invention to provide a flushing apparatus in which the valve mechanism and its controlling float are so organized and arranged that the valve will remain open to its fullest extent during the filling period, and will then be closed quickly for the purpose of avoiding the gradual closing and resulting hissing noise owing to the constricted aperture at the valve as the latter closes, and a further object is to provide a flushing tank with the parts so arranged that the washers of the valve are protected against unnecessary wear by slow closing movement of the valve.

With these and other objects in view, as will be readily apparent in the following specification, the invention consists of a flush tank having a suitable flushing outlet in its bottom, and a supply valve to fill the tank with water, and a float operable in a separate chamber from the flushing tank to rapidly close the supply valve after the tank proper has been filled to the desired level.

The invention further consists in means providing for various adjustments and providing for the adaptability of the parts of the apparatus to various types of tanks. The embodiment of the invention herein described is illustrated in the accompanying drawing in which the figure is a substantially central, vertical section through the apparatus with the parts in such position

that the supply valve is open and its controlling float is in the lowermost position, the tank having been emptied.

In the form of the invention illustrated, 10 the tank 2 represents a tank of suitable proportion, having in or adjacent its bottom an outlet 3 forming a seat for a flush valve 4 of suitable type which is adapted to be lifted to open the outlet 3

15 to which it appertains to make and use the same.

This invention relates to flushing apparatus, and particularly to flush tanks.

15 It is an object of the present invention to provide a flush tank in which the water tank for refilling the tank may enter through a valve which is normally open until the main tank is substantially filled with water and is then quickly closed by an automatic valve.

20 The important feature of the present invention resides in the means for controlling the supply valve 6, which is suitably mounted with relation to the tank 2, in the present form comprises the provision of a separate chamber or receptacle 10 disposed that after the tank 2 is filled, excess of water coming from the supply valve 6 will enter the auxiliary chamber and cause a float therein to rise subsequent to the filling of the tank 2, and thus quickly and almost instantly close the supply valve and cut off the supply of water. It is understood that this auxiliary chamber may be disposed in any relation to the valve and may

25 be of suitable shape, design and proportion and located as may be desired with relation to the tank 2. In the present case an auxiliary or float chamber 10 is shown as mounted at one end of the tank 2 and having at its lower portion a drain or outlet connection 11 provided with a check or drain valve

30 12, and within the chamber 10 there is provided a float 13 to which is adjustably connected a stem 14 extending upwardly through a guide 15 of suitable design, the upper end of the stem 14 being provided with an eye 16. To operate the valve 6 the latter is provided with an adjustable stem or lever 17 which extends in a suitable direction toward the chamber 10, and preferably is connected by an adjustable connection as at 18 to the eye 16 of the float stem 14. In the present instance the connection 18 comprises a substantially L-shaped arm 105 having an upwardly extending shank 19 with an elbow 20 adjustable on its upper end and in one arm of which elbow there is adjustably connected a shank 21 which passes through the eye 16 above the top of

the float chamber 10. After the flush valve 4 has been opened to permit the escape of water from the tank 2 through the outlet 3, the check valve 12 controlling the float chamber 10 will open under pressure of water in the chamber and all of the water be drained from the tank and the float chamber. As the float 13 falls in said chamber the lever arm 17 of the valve is lowered 5 so as to open the valve and permit water to enter and refill the tank 2 until it reaches a level approximately at the top of the float chamber 10 or suitable openings which may be provided therein if desired, so that after 10 the tank 2 is filled and before the valve 6 is fully closed an excess of supply water will flow into the chamber 10 to fill the other to the desired height with the resulting action that the float 13 will be lifted 15 and finally totally submerged by the water coming over the upper end or into the chamber 10. As the float 13 rises, and just prior to the closing of the valve 6, the check valve 12 is automatically opened to equalize the 20 level of the water in the main tank 2 and within the float chamber 10 through means of a suitable connection as a link 12' which is pivoted at its lower end to the check valve 12 and passes through an eye or slotted 25 extension 18' on the connection 18 at the end of the lever arm 17, the upper end of the link 12' being threaded as at 12^a and provided with an adjustable nut 12^b whereby the time of opening of the check or drain 30 valve 12 may be nicely determined by the relative position of the stop nut 12^b which is engageable by the eye 18' of the lever 17. 35 The operation of the device is substantially as follows: Assuming that the tank 40 has been emptied as shown in the present figure, and the valve 6 held in open position by the lowered float 13 and the lever arm 17, then the flush valve 4 has seated itself upon the outlet 3 and the incoming stream of 45 water flows through the valve 6 and rises within the tank 2, the drain or check valve 12 meanwhile being automatically seated over the outlet 12 to close the float chamber 10. The continual inflow of water causes 50 the rise of level in the tank 2 until an inlet opening or the open top of the chamber 10 is reached, after which the excess water from the tank 2 will flow into the float chamber 10 and causes the float 13 to rise, 55 lifting with it the lever arm 17 and thus quickly closing the valve 6. It will be seen from the foregoing that while the tank 2 is being filled the valve 6 is held in fully open position until tank 2 is filled to the desired 60 extent and that there will be no hissing noise due to the usual gradual constriction of the opening of the supply valve as occurs in such flush tanks in which the valve float is mounted in the tank proper and caused to 65 rise with the constantly varying level of the water. As soon as a sufficient quantity of water accumulates in the float chamber 10 the float is quickly lifted upward and rapidly closes the valve 6 and shuts off the flow of water. Just prior to the closing of the valve 6 there is an equalization of the levels of the water in the tank 2 and in the chamber 10 by the automatic opening of the check valve 12 through the engagement with the nut 12^b on the upper end of the valve link with the eye 18' of the lever arm 17. 70 From this it will be seen that we have provided a flushing tank in which the gradual closing of the supply valve is eliminated and the usual resultant hissing noise is overcome, 80 and at the same time the life of the washer of the valve is extended by the saving of the wear due to friction thereon under pressure of the water through the valve as it is gradually closing. 85 Another important advantage which is gained by the present apparatus, is that in the event of a leak through the outlet or flush valve 4, the supply valve will remain closed until the level of the water in the tank 2 and its associated float chamber 10 has been lowered to approximately one-half 90 the maximum height by reason of the fact that the float 13 when its chamber 10 is filled is totally submerged and acts to hold the valve closed during a considerable period during the gradual lowering of water in the various chambers due to leak. Then when this low level has been reached the valve will open and be quickly closed again as 100 soon as the float 13 is raised the necessary extent. 105 What we claim is:
1. A flushing apparatus comprising a tank and its flushing outlet and valve therefor, a supply valve having a lever, a float chamber with a drain valve leading to said tank, and adjustable connections between said lever and the float and the drain valve and providing for relative movement of each. 110
2. A flushing apparatus comprising a tank having a flushing outlet and a valve therefor, a separate chamber having a drain valve leading to the tank, a float in said chamber, a supply valve closable by the float in said chamber, and a connection between said drain valve and the supply valve providing for initial movement of the lever freely of the drain valve and operative to open said drain valve when the supply valve is nearly closed to establish free communication between said chamber and tank. 115
3. A flushing apparatus comprising a tank having a flushing outlet and a valve therefor, a separate chamber having a drain valve leading to the tank, a float in said chamber, a supply valve closable by the float in said chamber, and a connection between said drain valve and the supply valve pro- 120
125
130

viding for initial movement of the lever freely of the drain valve and operative to open said drain valve when the supply valve is nearly closed to establish free communication between said chamber and tank, said connection being adjustable to provide for variation of time of action of the drain valve by said lever.

4. A flushing apparatus comprising a tank having a flushing valve, a supply valve and its lever, and a separate or float chamber having a drain valve leading to said tank, and a float guided therein, adjustable connections between said float and valve lever and including a sliding joint, said

lever operatively connected to said drain valve.

5. A flushing apparatus comprising a tank having a flushing valve, a supply valve and its lever, and a separate or float chamber having a drain valve leading to said tank, and a float guided therein, adjustable connections between said float and valve lever and providing for relative movement, said lever operatively and adjustably connected to said drain valve. 20 25

In testimony whereof we affix our signatures.

LE ROY BALL.
AUGUSTUS L. McLEAN.
